[57] **CLAIM**

The ornamental design for a ball elevation golf tee, as shown and described.

DESCRIPTION

FIG. 1 is a front, top and side exploded perspective view of the ball elevation golf tee showing my new design;

FIG. 2 is a front elevational view thereof in the assembled condition, the rear being a mirror image of the front shown in FIG. 2 with the exception of the alignment hole;

FIG. 3 is a side elevational view thereof;

FIG. 4 is a side elevational view thereof;

FIG. 5 is a top plan view thereof; and,

FIG. 6 is a bottom plan view thereof.

FIG. 2

FIG. 3

FIG. 4

FIG. 5

FIG. 6
